UNITED STATES PATENT OFFICE.

GEORGE JOHN, OF WHEELING, WEST VIRGINIA.

RECOIL-LOADING RIFLE.

1,121,633.

Specification of Letters Patent. Patented Dec. 22, 1914.

Application filed September 2, 1913. Serial No. 787,584.

To all whom it may concern:

Be it known that I, GEORGE JOHN, a subject of the Sultan of Turkey, and resident of Wheeling, county of Ohio, and State of 5 West Virginia, have invented certain new and useful Improvements in Recoil-Loading Rifles, of which the following is a specification.

This invention relates broadly to firearms, and specifically to a rifle of the magazine type.

The primary object of the invention is to provide a recoil-loading rifle of simple and comparatively inexpensive construction.

15 A further object is to provide a rifle of the character mentioned which is so constructed that the cartridges contained therein will be automatically moved to firing position and fired in rapid succession during 20 the time that the trigger occupies retracted, or drawn position.

With these and other objects in view, the invention resides in the features of construction, arrangement of parts and combinations 25 of elements which will hereinafter be exemplified, reference being herein had to the accompanying drawings, forming a part of this specification, in which—

Figure 1 is a top plan view of a rifle embodying my invention; Fig. 2 is a side elevation of the same; Fig. 3 is an enlarged top plan view of the operating parts with the top cover plate removed; Fig. 4 is a longitudinal section; Fig. 5 is a similar section of the breech mechanism, enlarged, 35 taken on the line 5—5, Fig. 3; and Fig. 6 is a similar section taken on the line 6—6, Fig. 3.

Referring to said drawings, in which like 40 designating characters distinguish like parts throughout the several views—1 indicates the barrel and 2 the stock, the latter having removably mounted therein a metallic casing 3 constituting a magazine adapted for 45 containing a relatively large number of cartridges 4, the latter being received therein in positions inclined with respect to said magazine casing and in parallel alignment with the bore in the barrel. A coil spring 5 is 50 located within said casing and exerts a constant pressure against a movable beveled seat 6 by means of which said cartridges are advanced.

Mounted to operate between suitable

guides 7 fixed in position at opposite sides 55 of the loading chamber 11, so as to be slideable longitudinally in line with the bore in the barrel is a breech-piece 8 having an upwardly directed integral extension 8^a on the top thereof in which is loosely mounted the 60 front end of a stationary bolt or stem 9 which lies parallel to said guide-piece 7 and has its rear end seated in a plate 10 mounted upon the top of the stock adjacent to the rear end of said loading chamber 11. A 65 coil spring 12 encircling said stem 9 has its rear end seated against said plate 10 and its front end seated against said extension 8^a and acts to normally maintain said breech-piece 8 thrust forward against the 70 end of the barrel, as shown in Figs. 3, 4 and 5. Oppositely disposed laterally projecting arms 8^b afford means whereby said breech-piece may be grasped for retracting the latter by hand when such is desired. Provided 75 in said breech-piece is a small longitudinally extending bore 13 which aligns centrally with the bore in the barrel, and slideable within said bore 13 is the front end of a firing-pin 14 the rear end of which lies within a socket 15 provided in the stock at the rear end of the loading chamber. Fixed on said firing-pin at a suitable point is a collar 16 having at one side thereof a laterally directed arm 17, and interposed between 80 said collar and the inner end of said socket and in encircling relation to said firing-pin is a coil spring 18 adapted for normally holding said firing-pin in a forwardly thrust position. When said pin is forced back 85 against the tension of said spring, as shown in Figs. 4 and 5, said arms 17 engages and interlocks with the rear end of a bar 19 which is supported by, and has rocking movement on, a vertically-disposed headed 90 pin or pivot 20 at a point intermediate its ends. A small coil spring 21 seated beneath said rear end of the bar 19 normally maintains the said rear end elevated in bar-engaging position, as shown in Figs. 3, 5 and 6. 100

The trigger 22 is pivoted intermediate its ends, as shown in Fig. 6, and has pivotally connected to its upper end the lower end of an upwardly and forwardly inclined bar 23 the opposite end of which underlies the 105 front end of pivoted bar 19, said bar 23 being adapted, when the trigger 22 is drawn, to elevate the front end of bar 19, causing

the latter to assume a substantially horizontal position against the tension of spring 21 and releasing the interlocking engagement therewith of the arm 17. When so released, the firing pin is forcibly thrust forward by the spring 18 for firing the cartridge seated in the bore of the barrel.

The recoil produced by the firing of a cartridge thrusts the breech-piece 8 rearward against the stock at the rear end of the loading chamber, carrying therewith, against the tension of its spring 18, the firing-pin 14. Assuming that the trigger 22 has been released, the laterally extending arm 17 again interlocks with the end of bar 19, and, actuated by the spring 12, said breech-piece is returned to its normal forwardly thrust position. If, however, the trigger is held in drawn position, the firing pin is immediately re-advanced for firing the next cartridge which has, in the interval between the rearward movement of the breech-piece, due to the recoil, as aforesaid, and the return of the breech-piece, been advanced into firing position. The empty cartridge follows the movement of the breech-piece with the recoil of the gun, and is by the force of the back-acting air thrust laterally outward through an opening 24 provided in one of the face plates 25, said opening being the only outlet through which said force may be relieved, or permitted to escape. The spring 5 maintains the cartridges in the magazine casing in a forwardly thrust position with the foremost thereof directly underlying the breech-piece 8; and, when said breech-piece has been thrust rearward under the action of the recoil, said foremost cartridge is elevated to a position directly in front of the breech-piece, and, when the latter returns to normal position, is thereby advanced into firing position in the bore of the barrel. A removable cover-plate 26 is suitably mounted in overlying relation to the loading chamber, as shown.

Having thus described my invention, what

I claim as new, and desire to secure by Letters Patent, is—

A recoil loading rifle, comprising, a barrel, a stock having a loading chamber, guides formed in the chamber, a breech piece engaging said guides and reciprocal in said chamber, an extension formed upon the upper surface of the breech piece, a plate mounted on the stock, a stem having its rear end fixed to the plate and its forward end slidably engaged with said extension, a coil spring encircling the stem, and having its respective ends bearing against the plate and extension to hold the breech piece thrust yieldably forward, a bore formed in the breech piece, a socket formed in the stock and aligned with said bore, a firing pin having one end supported by and slidably engaged in the socket and its other end similarly engaged in said bore, a collar fixed to the firing pin, a spring encircling one end of the stem and retractile in the socket, an arm fixed to the collar, a bar pivotally supported in the loading chamber the rear end of which is adapted to engage said arm to hold the firing pin inoperative, a trigger bar slidably engaging the forward end of said bar to rock the same, thereby freeing the arm to permit the firing pin to move to its firing position, said breech piece being moved rearwardly in the loading chamber upon the explosion of a cartridge, the recoil imparted to said breech piece serving to rock the bar so that said arm interlocks with the rear end of the said bar, and means for feeding cartridges to the bore of the barrel upon recoil of the breech piece.

In testimony whereof, I affix my signature in presence of two subscribing witnesses.

GEORGE X JOHN.
